UNITED STATES PATENT OFFICE

158,128

INTERCOMMUNICATION TELEPHONE STATION CABINET

Owsiej Plawczyk, London, England

Application January 21, 1949, Serial No. 381
In Great Britain September 22, 1948

Term of patent 14 years

(Cl. D26—14)

To all whom it may concern:

Be it known that I, Owsiej Plawczyk, a subject of the King of Great Britain, residing at 78 Brondesbury Road, London, N. W. 6, England, have invented a new, original, and ornamental Design for an Intercommunication Telephone Station Cabinet, of which the following is a specification, reference being had to the accompanying drawing, forming part thereof:

Fig. 1 is a perspective front elevational view of an intercommunication telephone station cabinet showing my new design.

Fig. 2 is a perspective rear elevational view thereof.

Fig. 3 is a perspective view thereof, with the device stood on one end to show the base.

I claim:

The ornamental design for an intercommunication telephone station cabinet, as shown.

OWSIEJ PLAWCZYK.
